UNITED STATES PATENT OFFICE.

RICHARD H. DAWSON, OF ROCKVILLE, CONNECTICUT.

IMPROVEMENT IN FLOCK-CLEANING MACHINES.

Specification forming part of Letters Patent No. 140,684, dated July 8, 1873; application filed October 16, 1872.

To all whom it may concern:

Be it known that I, RICHARD H. DAWSON, of Rockville, in the county of Tolland and State of Connecticut, have invented a new and useful Improved Flock-Cleaning Machine, of which the following is a specification, reference being had to the accompanying drawings, in which—

Figure 1 is a side elevation. Fig. 2 is a plan view.

In the process of forming a nap on cloths there are produced what are known as flocks, which are matted together and contain a great number of teazle-points. My invention is a machine for loosening up these flocks, and cleaning out the teazle-points.

The letter *a* indicates the frame of the machine. *b* is the main shaft, to which power is applied by means of a belt running on the pulley *b*¹. The other pulley *b*² is a common loose pulley. Power is communicated to the shaft *c* by a belt running from the pulley *b*³ to the pulley *c*¹. The belt *d*² communicates power from the pulley *b*⁵ to the pulley *d*¹ and shaft *d*. The belt *e*² communicates power from the pulley *b*⁴ to the pulley *e*¹ and shaft *e*. The belt *f*² communicates power from the pulley *b*⁶ to the pulleys *f*¹ and *f*, and the belt *g*², running from the pulley *f*, communicates power to the pulley *g*¹ and shaft *g*. The flock is fed to the machine upon the endless apron *h*, which runs upon the roll *h*¹, and a similar roll upon the shaft *g* being propelled by the latter. This apron brings the flock up against the brush-cylinder *c*², which is a cylinder covered with a brush, and revolves in the direction indicated by the arrow. The brush, thus revolving, catches the flock and carries it around upon its surface. It travels thus but a little way before it comes in contact with the teeth of the comb *i*, which extends quite across the face of the brush-cylinder, its ends set in the guide or side boards *j*, and so arranged as to be adjustable toward and from the surface of the brush-cylinder. The effect of the catching of the flock against this comb is to loosen it up and separate the fibers. A little further on the flock strikes against a second comb, *i*¹, which is set a little nearer to the face of the

brush than the comb *i*. In like manner the flock strikes against a third comb, *i*², which is set nearer to the brush than the comb *i*¹, and by this time the flock is thoroughly loosened up. After passing all these combs the flock is carried against the card-tooth cylinder *k*, which is covered with what is known to cloth-makers as card-clothing. It revolves in the direction indicated by its arrow, but much more slowly than the cylinder *c*², so that the flock catches in the hooks of the card-clothing, while the brush-cylinder *c*² brushes out all the teazle-points. The brush-cylinder *l* continues and perfects the operation of brushing out the teazle-points. The flock thus cleared of its teazle-points passes on with the cylinder *k* till it comes to another brush-cylinder, *m*, which is so set that its bristles mesh into the hooks of the cylinder *k*, thus availing to brush the flock out from the hooks so that it falls down and is conveyed away by the spout *n*. The cylinders *c*² and *l* are set so that their bristles but just meet or fall a trifle short of the hooks on the cylinder *k*. The teeth of the comb *i*¹ are longer than those of the comb *i*, and those of the comb *i*² are somewhat longer than those of the comb *i*¹.

I claim as my invention—

1. The combination of the rotating brush-cylinder *c*² with the overlying stationary combs *i* *i*¹ *i*², one or more, both constructed, arranged, and designed to operate substantially as described, for the purpose set forth.

2. The combination of the rotary brush-cylinder *c*², the overlying combs *i* *i*¹ *i*², one or more, and the card-toothed cylinder *k*, all constructed, arranged, and designed to operate substantially as and for the purpose set forth.

3. The combination of the brush-cylinder *c*², the overlying combs *i* *i*¹ *i*², one or more, the card-toothed cylinder *k*, and the brush-cylinder *m*, rotating in the same direction with the card-toothed cylinder, the whole constructed, arranged, and designed to operate substantially as and for the purpose set forth.

RICHARD H. DAWSON.
